(57) **CLAIM**

The ornamental design for an electronic therapy device, as shown and described.

DESCRIPTION

FIG. 1 is a perspective view from above showing a first embodiment of an electronic therapy device in accordance with the present invention.

FIG. 2 is a front view showing the electronic therapy device of FIG. 1.

FIG. 3 is right side view of the electronic therapy device of FIGS. 1-2.

FIG. 4 is a left side view of the electronic therapy device of FIGS. 1-3.

FIG. 5 is a rear view of the electronic therapy device of FIGS. 1-4.

FIG. 6 is a top view of the electronic therapy device of FIGS. 1-5; and,

FIG. 7 is a bottom view of the electronic therapy device of FIGS. 1-6.

1 Claim, 6 Drawing Sheets

FIG. 1

FIG. 3

FIG. 4

FIG. 5

FIG. 6
